UNITED STATES PATENT OFFICE

HAROLD HOWE, OF NEW YORK, N. Y., ASSIGNOR TO HOWE FOLDING FURNITURE, INC.,
OF NEW YORK, N. Y.

FOLDING CHAIR

Application filed May 5, 1931. Serial No. 535,168.

My invention relates to a folding device for furniture and the like and is particularly adaptable for folding chairs, tables, beds, shelves, benches, etc.

5 The primary object of my invention lies in the provision of a link mechanism so arranged as to provide for the parts or surfaces to be folded with respect to each other, a very positive as well as synchronized folding movement.

10 The device is especially applicable to foldable parts which comprise a pair of supporting surfaces or elements and which are adapted to be folded to substantially parallel relation with and adjacent to a relatively fixed third surface.

15 Another feature of my invention lies in the provision of a novel locking device which cooperates with the folding link mechanism to rigidly lock it in one position whereby accidental or inadvertent displacement thereof is prevented.

20 Other objects and advantages in details of construction and arrangement of parts will be apparent as the description proceeds, reference now being had to the figures of the accompanying drawings forming a part of this application and wherein like reference numerals indicate like parts.

25 In the drawings:

Figure 1 is a perspective view of my improved folding mechanism shown in cooperative relation with a chair outlined in phantom.

30 Figure 2 is a side view of a chair equipped with my invention.

Figure 3 is a front plan view of the chair with the seat and front legs raised or folded adjacent the chair back and frame.

35 Figure 4 is a detail side view taken on the line 4-4 of Figure 1 showing a portion of the locking mechanism.

Figure 5 is a detail sectional view of the locking mechanism.

40 The reference characters 1, and 2, refer to the front legs of the chair and the references 3 and 4 to the rear legs thereof. The rear legs 3 and 4 extend upwardly as at 5 to provide a back frame and connecting these extended portions is the back rest 6. A seat 7

is pivoted to the back frame as by means of the pins 8 on which are journaled the ears 9 of a metal piece 10 carried at the rear edge of the seat 7. The seat 7 may be cut out as at 11 at its rear corners to receive the extensions 5 of the rear legs thus providing a full width seat.

45 The rear legs 3 and 4 may be connected also by means of the cross braces 12 and 13 for stability.

50 The front legs 1 and 2 are connected at their upper ends by a cross brace 14 to which is hinged as at 16 the seat 7. The front legs 1 and 2 are, therefore, foldable as a unit with respect to the underside of the seat 7.

55 Pivoted at one end to each of the front legs 1 and 2 and the rear legs 3 and 4 are the links 16, 17, 18, and 19 respectively. The opposite ends of these links are provided with a common pivot 20 positioned substantially centrally of the underside of the seat 7. A link 21 is likewise pivoted to this common pivot pin 20 at one end and at its opposite end is pivoted to the vertical depending flange 22 of an angle strip 23 suitably secured as by 60 screws 24 to the underside of the chair seat 7. Thus there is provided a series of links pivotally connected at one end with the chair legs and seat and provided at their opposite ends with a free common pivot. The result of this 65 arrangement is that if the chair seat is lifted for folding back against the back of the chair, the front legs 1 and 2 will be positively and synchronously folded therewith to the position shown in dotted lines in Figure 2 and in 70 full lines in Figure 3. Likewise when the seat 7 is lowered the front legs will be positively and synchronously unfolded therefrom to seat supporting position as in Figures 1 75 and 2.

75 Although this invention has been illustrated in connection with a chair, it is to be understood that it is not limited thereto inasmuch as the folding portions 7 and 1-2 of the chair illustrated herein might well be surfaces foldable in connection with a rear surface corresponding to the rear legs and frame of the chair, but used for an entirely different purpose. For instance, the same link application 80 would be effective in folding and un-

folding the parts or surfaces of a shelf with respect to a wall, a table, ironing board, or wall bed and the like.

Means are also provided whereby the folding mechanism may be releasably locked in one position.

Fixed upon one side of the vertical flange 22 of the angle bracket 23 is a headed pin 25. Slidable along one side of this depending flange of the angle bracket is one end of a locking bar 26 provided with a slot 27 within which the pin 25 is positioned, thus providing for a guided sliding movement of the locking bar 26. Spaced a short distance from the slot 27 in the bar 26 is a pin member 28 extending laterally of the bar. This pin is adapted to cooperate with a notch or recess 29 in one end of the flange 22. A coil spring 30 has one end secured to the headed pin 25 on the flange 22 and its opposite end secured to the pin 28 on the locking bar, whereby to normally urge the pin 28 into engagement with the recess 29.

A link 31 is pivotally connected as at 32 to the locking bar 26 and at its opposite end to the common pivot 20 of the links 17, 18, 19 and 21.

The locking bar 26 immediately forward of the link 31 is twisted or bent as at 33 whereby the same will lie flat from that point forwardly to a point immediately in the rear of the cross brace 14, where the bar is turned downwardly as at 34 to provide a finger piece immediately in back of the cross piece 14. By this means the locking bar can be manipulated, that is pulling forwardly against the tension of the spring 30 to release the pin 28 from the recess 29 and permit the folding action above described.

As the seat and front legs are folded downwardly again to supporting position, the pin 28 finds its seat in the recess 29 and thus locks the link mechanism against folding movement without operation of the locking bar.

Of course, changes may be made in details of construction without departing from the spirit and scope of my invention. I do not limit myself, therefore, to the exact form herein shown and described other than by the appended claims.

Claims:

1. A folding chair comprising a back and rear legs, a seat pivoted thereto, front legs pivoted to said seat, and means connecting said legs and seat whereby movement of said seat to and from folded position causes positive and synchronous movement of said front legs, said means comprising links pivoted at one end to said seat and legs and to a free common pivot at their opposite ends said pivot being disposed directly under said seat and substantially centrally thereof.

2. A folding chair comprising a back and rear legs, a seat pivoted thereto, front legs pivoted to said seat, means connecting said

legs and seat whereby movement of said seat to and from folded position causes positive and synchronous movement of said front legs, said means comprising links pivoted at one end to said seat and legs and to a free common pivot at their opposite ends, said pivot being disposed directly under said seat and substantially centrally thereof, and means for locking said links, seat, and legs against movement in one position.

3. In combination, a folding mechanism for three members, the first of said members being pivotally connected at substantially a right angle to the second member and the second member being pivotally connected at substantially a right angle to the third member, three links each pivoted to one of said members, and all of said links having a free common pivot disposed substantially centrally under said second member.

4. A folding chair comprising a back and rear legs, a seat pivoted thereto, front legs pivoted to said seat, separate links pivoted at one end to each of said legs and seat, and a free common pivot for the opposite ends of all of said links, disposed substantially centrally of the underside of said seat.

5. A folding chair comprising a back and rear legs, a seat pivoted thereto, front legs pivoted to said seat, and means connected at one end with said legs and seat and converging therefrom to a common element disposed substantially centrally under said seat whereby movement of said seat to and from folded position causes positive and synchronous movement of said front legs.

In testimony whereof, I affix my signature.
HAROLD HOWE.
